UNITED STATES PATENT OFFICE.

WILLIAM A. WHITLOCK, OF UKIAH, CALIFORNIA.

SURGICAL INSTRUMENT.

No. 928,011.

Specification of Letters Patent.

Patented July 13, 1909.

Application filed December 31, 1908. Serial No. 470,207.

To all whom it may concern:

Be it known that I, WILLIAM A. WHITLOCK, a citizen of the United States, residing at Ukiah, in the county of Mendocino and 5 State of California, have invented certain new and useful Improvements in Surgical Instruments, of which the following is a specification.

This invention relates to an improved surgical instrument, the same consisting of a 10 curette for uterine purposes; and the invention has for its object to provide an instrument of this kind which shall be simple in construction, effective in operation, may be 15 inserted or introduced through the cervix of the uterus without necessitating the application of force in order to accomplish the necessary dilation as when a common curette is used, and which may be readily disassembled or taken apart in order that the parts 20 or members may be carefully and effectively cleansed and sterilized.

Further objects of the invention are to simplify and improve the construction of this 25 class of devices.

With these and other ends in view which will readily appear as the nature of the invention is better understood, the same consists in the improved construction and novel 30 arrangement and combination of parts which will be hereinafter fully described and particularly pointed out in the claims.

In the accompanying drawings has been 35 illustrated a simple and preferred form of the invention; it being, however, understood that no limitation is necessarily made to the precise structural details therein exhibited, but that changes, alterations and modifications within the scope of the invention may 40 be resorted to when desired.

In the drawings—Figure 1 is a side elevation of an instrument constructed in accordance with the invention. Fig. 2 is a perspective view showing the instrument in condition for use and illustrating one position of the curette or scraper. Fig. 3 is a perspective detail view of one end of the instrument, showing another position of scraper. Fig. 4 is a detail view showing in side elevation the 45 parts or members comprising the expanding rod separated from each other. Fig. 5 is a detail side elevation of the sheath. Fig. 6 is a perspective detail view showing the spring which constitutes the curette or scraper, detached. Fig. 7 is a detail view illustrating a 50 modification. Fig. 8 is a transverse sec-

tional view taken on the plane indicated by the line 8—8 in Fig. 1. Fig. 9 is a sectional detail view taken on the plane indicated by the line 9—9 in Fig. 8.

Corresponding parts in the several figures are denoted by like characters of reference.

In the construction of the improved instrument any suitable material, preferably metal, may be employed, it being premised that if non-corrodible material is not used, it may and is preferably protected against corrosion, by plating or in some other suitable well-known manner. This, however, is left to the option of the manufacturer.

5 designates a tubular sheath of suitable dimensions which is preferably provided at one end with a reinforcing band 6, having a threaded aperture for the passage of a setscrew 7. The end of the sheath which is 75 equipped with the band 6 will, for convenience, be designated as the outer end.

Extending longitudinally through the sheath 5, and slidably therein, is a rod 8, which may be called the expanding rod, and 80 which is provided at its outer end, adjacent to the outer end of the sheath, with a handle 9. The opposite or inner end of the expanding rod is provided with a screw-threaded socket 10, for the reception of a 85 correspondingly threaded nipple 11, formed upon a detachable member 12, which constitutes an extension of the expanding rod and which is provided at the extremity thereof with an expanded portion 13 having a slot 90

14, said expanded and slotted portion constituting a stirrup for the reception of one end of the scraper 15. The latter consists of a flat spring of suitable dimensions, formed preferably of fine steel and having at 95 one end a loop or coil 16, which may readily be placed in engagement with the slot and with the cross-bar at the extremity of the stirrup-member of the expanding rod. The resiliency of the material of which it is 100 formed will enable the loop or coil 16 to be readily sprung into engagement with, or detached from the stirrup-member, as may be required, and when placed in effective engagement it will be retained with sufficient security for all practical purposes. It will be understood that the reason for making the stirrup-member 12 separable from the expanding rod is simply this that the width of the expanded portion constituting the 110 stirrup would prevent its passage through the sheath; hence the necessity for making

the parts separable, and for connecting them subsequent to the insertion of the rod 8 through the sheath or casing.

The sheath or casing 5 has been shown as 5 being provided adjacent to its inner end with a slightly bulging band or bulb 17, having a longitudinal slot or recess 18 for the reception of the end of the spring 15, which is not connected with the stirrup-member, the 10 spring being secured in the slot 18 by suitable means such as a set-screw 19, which, however, must be entirely countersunk or confined in the bulb or band 17, so as to present no projecting portion that might scratch or 15 injure the tissues or membranes with which it may come in contact. It will be understood that any suitable means may be utilized for connecting the end of the spring 15 detachably with the end of the sheath 20 and it is desired to be further understood that within the scope of the invention the end of the spring 15 may be attached permanently to the sheath, as by brazing or soldering in connection with a band or ferrule, as shown at 20, in Fig. 7 of the 25 drawings.

It will be understood that when the ends of the spring 15 have been connected, respectively, with the sheath and with the expanding rod, the said spring may be manipulated to constitute a loop to which different shapes and dimensions may be given, as shown at L and L', respectively, in Figs. 2 and 3 of the drawings; the variation in the form of the 35 loop being effected by sliding or adjusting the rod 8 longitudinally within the sheath, where the said rod may be secured at any desired adjustment by means of the set screw 7. It will furthermore be seen that by 40 projecting the rod 8 through the sheath, the spring 15 may be caused to lie flat upon or adjacent to the side of the inner end of the expanding rod, as shown in Fig. 1 of the drawings; when the instrument is in this 45 condition it is obvious that it presents no obstruction that will interfere with its passage through the cervix of the uterus without resorting to any unnecessary and painful dilation. After the introduction of the 50 instrument the rod 8 may be projected through the sheath, thus flexing the spring 15 until it forms a loop of the desired shape and di-

mensions, after which the instrument may be manipulated by rotation or in any other manner to accomplish the desired results. 55 If desired, one or both edges of the spring constituting the scraper may be sharpened for the purpose of facilitating the removal of the placenta or morbid matter from the membrane or lining. 60

From the foregoing description taken in connection with the drawings hereto annexed, the operation and advantages of this invention will be readily understood. The construction is simple and thoroughly effective, 65 and an instrument is provided the utility and advantages of which will be at once recognized by the medical practitioner. An important advantage of this improved instrument resides in the facility with which its 70 component parts or members may be disassembled or separated for the purpose of cleaning and sterilizing the same; and it will furthermore be seen that any of the parts, if broken or injured, may be very readily replaced at a comparatively trifling expense. 75

Having thus described the invention, what is claimed is—

1. A device of the class described, comprising a tubular sheath, a rod movable longitudinally in the sheath, and having a handle at one end, a stirrup-member connected detachably with the other end of the rod and a flat spring connected at one end with the sheath and having at the other end a loop adapted to be separably connected with the stirrup-member. 80

2. A device of the character described, comprising a tubular sheath, a rod movable longitudinally in the sheath and having at 90 one end a stirrup-member detachably connected therewith, a longitudinally slotted band mounted upon the sheath, a flat spring having one end engaged with the slotted band and provided at its opposite end with a 95 loop or coil adapted for detachable connection with the stirrup-member, and means for securing the spring in the slotted band.

In testimony whereof I affix my signature in presence of two witnesses.

WILLIAM A. WHITLOCK.
